HYDRAULIC PRESSES

Will Huettner, Krefeld, Germany, assignor to Herbert van Huellen and Alfred van Huellen, trading as the firm Niederrheinische Maschinenfabrik Becker & van Huellen

Filed Feb. 11, 1959, Ser. No. 792,553

Claims priority, application Germany Feb. 22, 1958

3 Claims. (Cl. 100—214)

The invention concerns a hydraulic press which has a conventional stationary bedplate and a press table capable of being lifted and lowered. A single controlled hydraulic working cylinder adapted to engage the center of the press table may suffice for the movement thereof. Usually, however, several hydraulic working cylinders are disposed as symmetrically as possible about the center of the press table.

Apart from the exceptional case which is only possible with multi-cylinder presses where, as is known, owing to a non-uniform impact of the hydraulic working cylinder the press table may be brought into a position inclined to the bedplate during the working stroke, the press table is normally moved in planes parallel to the bedplate. In order to secure it moreover against undesired tilting out of this position, the press table is usually guided with its side surfaces or corners on corresponding upright counter-surfaces of the press frame. These fail, however, if the press table assumes, for any reason at all, an inclined position relative to the bedplate during the working stroke. The press table can easily jam in guides of this kind which leads at least to disruptions of this operation, as a rule even to severe damage of the press. An unintentional inclined condition of the press table relative to the bedplate occurs for example when the material being pressed has a non-uniform thickness, its upper surface being therefore inclined to its lower surface.

An object of the present invention is to provide a press-table guide which, on the one hand, safeguards the press table during its working and idle strokes against excessive tilting out of its plane-parallel condition relative to the bedplate and, on the other hand permits an inclined position of the press table relative to the bedplate without danger of jamming.

Another object of the invention is to provide a press which is simple and reliable in operation, with a further aim of constructing the press-table guide in such a way that it exerts on the press table, if the latter assumes an inclined position, a restoring force for bringing it back into a plane parallel to the bedplate.

According to the present invention a hydraulic press comprises a stationary bedplate and a press table, the latter being movable by means of a plurality of controlled hydraulic working cylinders either in a plane parallel to the bedplate or in an inclined condition relative thereto, the press table carrying at least one guide rod of such length and construction that its free end extends for a sufficient distance beyond the press table to a stationary press part and is adapted to bias the press table towards a parallel position relative to the bedplate whilst being elastically yielding it permits an inclined position of the press table relative to the bedplate. A slide bearing accommodates the guide rod so that its axis is exactly perpendicular to the bedplate in the plane-parallel position of the press table.

The invention will be described further, by way of example, with reference to the accompanying drawing, in which:

FIGS. 1 and 2 are vertical sections through a hydraulic press in different positions of the press table relative to

2

the bedplate, these views being taken on the line I—I of FIG. 3;

FIG. 3 is a horizontal section through the press taken on the line III—III of FIG. 1;

FIGS. 4 and 5 are vertical sections, similar to FIGS. 1 and 2, through a hydraulic press of modified construction, taken on the line IV—IV of FIG. 6; and

FIG. 6 is a horizontal section through the press taken on the line VI—VI of FIG. 4.

10 In both embodiments a press cross beam 2 is rigidly disposed on a stationary press frame 1; a vertically movable press table 3 is operated by a controlled hydraulic working cylinder 4. Guide rods 5 are fixed to the press table 3 and their slide bearings 6 are disposed on a stationary press part namely the bedplate 2 (FIGS. 1, 2) or the press frame 1 (FIGS. 4—6). The slide bearing 6, which in the plane parallel position of the press table 3 has its axis perpendicular to the bedplate 2 above or beneath a fixing point 7 of the associated guide rod 5 on the press table 3, has a convex inner surface 6a (exaggerated in the drawing) which defines a passage whose width equals that of the associated rod 5 at the center of this passage and progressively increases towards both ends thereof. The guide bars 5 are free from stress 20 only if the press table moves in plane-parallel position relative to the bedplate 2. Thus the guide bars 5 try to retain the press table 3 in the plane-parallel condition or to return it into this condition.

If, however, for any reason at all the press table 3 30 should perform a working stroke in the inclined condition relative to the bedplate 2 (FIGS. 2 and 5), the or each guide bar 5 must yield since its fixing point 7 on the press table in the inclined position thereof moves out towards one or other direction relative to the associated 35 slide bearing 6. Having regard to the maximum inclined position of the press table 3 and the maximum pressure force exerted by each working cylinder 4, the guide bar 5 can be so constructed that, especially by appropriate dimensioning of its cross section, on the one hand it

40 exerts on the press table a sufficient restoring force into the plane-parallel position relative to the bedplate 2 and, on the other hand, it permits, without excessive resistance against flexure, an inclined positioning of the press table 3 relative to the bedplate 2.

45 The embodiment shown in FIGS. 1 to 3 has a substantially rectangular press table 3 which, at each of two sides on which no charging or unloading of the press occurs, is provided with a rigidly arranged projection 8. To each projection 8, which preferably can be formed 50 as a lug cast onto the press table 3 or welded on to it, there is rigidly fastened at 7 the upwardly extending guide rod 5 which with its free end extends into the slide bearing 6 rigidly disposed on the bedplate 2. The guide rod 5 and the slide bearing 6 are thus disposed outside 55 the press space and do not hinder the charging and unloading of the press or the pressing operation itself. If the press table 3 is disposed in a plane-parallel position relative to the bedplate 2 (FIG. 1), each slide bearing 6 has its axis truly perpendicular to the table above the 60 fixing point 7 of the associated guide rod 5.

In the embodiment shown in FIGS. 4 to 6, in contradistinction to the first embodiment shown in FIGS. 1 to 3, the press table 3 carries a depending centrally disposed guide bar 5, the slide bearing 6 of this rod being fixed 65 in a housing 6b to the press frame 1. The slide bearing 6 is disposed in the same position relative to the fixing point 7 of the associated guide bar 5 on the press table 3 and, if desired, at the same spacing from this point as in the first embodiment.

70 Instead of a single guide rod 5 disposed in the center of the press table, at the intersection of the median longitudinal and median transverse planes 10 and 11, there

can also be provided several guide rods lying symmetrical-
ly relative to this intersection. For example, two guide
rods may be arranged in either or both planes 10 and 11.

If the press table 3 performs a working stroke and
therefore is moved in the direction towards the bedplate
2 in the first embodiment, the stressed length of the guide
rod 5 is shortened between the points 7 and 6, whilst in
the second embodiment it is increased. With this the
flexural resistance of the guide rod is increased in the first
case and reduced in the second case. This bar can if
necessary, according to known rules of mechanics, be
formed in such a way that its flexural resistance remains
approximately the same whereby the restoring force ex-
erted by it on the press table 3, urging it from the inclined
position into the plane-parallel position relative to the
bedplate 2, also remains constant within the limits in
which its stressed length changes during a working stroke
of the press table.

Conveniently either the internally curved slide bearing
6 in its housing 6b, or the housing itself, can be pivotably
mounted on the associated press part.

I claim:

1. In a press, in combination, a stationary structure
including a frame and a bedplate fixed to said frame, a
tiltable table displaceable on said frame toward and
away from said bedplate, power means engaging said
frame and said table for reciprocating the latter relatively
to said bedplate, a normally straight guide rod of limited
resilient deformability extending generally in the direc-
tion of reciprocation of said table, a mounting rigidly
securing a first part of said rod to said table, and a bearing
for a second part of said rod secured to said structure
at a location spaced from said mounting but aligned
therewith in the direction of reciprocation of said table,
said table and said bedplate having confronting work-
engaging surfaces normally parallel to each other and
perpendicular to said direction of reciprocation, said bearing
engaging said rod along a single narrow peripheral zone of
the latter while enabling limited flexural deformation
of said rod in response to a tilting of said table by
said power means upon the engagement of a workpiece
with beveled sides by said confronting surfaces, said

bearing having convex internal walls forming a passage
of a width equaling that of said rod at an intermediate
cross section, the width of said passage increasing pro-
gressively from said intermediate cross section toward its
ends.

2. In a power press, in combination, a stationary struc-
ture including a frame and a bedplate fixed to said frame,
a tiltable table displaceable on said frame toward and
away from said bedplate, fluid-operated means engaging
said frame and said table for reciprocating the latter relatively
to said bedplate, a normally straight guide rod of limited
resilient deformability extending generally in the direc-
tion of reciprocation of said table, a mounting rigidly
securing an extremity of said rod to said table, a bearing
for said rod secured to said structure at a location
spaced from said mounting but aligned therewith in the
direction of reciprocation of said table, said table and
said bedplate having confronting work-engaging surfaces
normally parallel to each other and perpendicular to said
direction of reciprocation, said bearing having convex
internal walls forming a passage of a width equaling
that of said rod at an intermediate cross section, the
width of said passage increasing progressively and sub-
stantially symmetrically from said intermediate cross
section toward its ends whereby said bearing engages
said rod along a single narrow peripheral zone of the
latter while enabling limited flexural deformation of said
rod in response to a tilting of said table by said fluid-
operated means upon the engagement of a workpiece with
beveled sides of said confronting surfaces.

3. The combination according to claim 2 wherein the
axis of said rod in its normal position lies in a median
plane of said table, said fluid-operated means comprising
a pair of hydraulic units bearing upon said table on
opposite sides of said median plane.
